UNITED STATES PATENT OFFICE.

WILLIAM H. ROWLING, OF OAKLAND, CALIFORNIA.

TRAFFIC-SIGNAL FOR MOTOR-VEHICLES.

1,311,418.

Specification of Letters Patent. Patented July 29, 1919.

Application filed May 28, 1918. Serial No. 237,019.

To all whom it may concern:

Be it known that I, WILLIAM H. ROWLING, citizen of the United States, residing at Oakland, in the county of Alameda and 5 State of California, have invented certain new and useful Improvements in Traffic-Signals for Motor-Vehicles, of which the following is a specification.

This invention relates to an improved 10 traffic signal for motor vehicles and has as its primary object to provide a construction employing companion signaling devices which may be connected to the frame of the wind shield of the vehicle or other convenient points thereon and adapted to be 15 manually operated for indicating an intention of the driver to turn either to the right or left or an intention to stop.

The invention has as a further object to 20 provide signaling devices each employing a semaphore blade and wherein the said blade may be readily swung to active or inactive position to be automatically locked in each of such positions.

25 And the invention has as a still further object to provide a construction wherein the semaphore blade of each of the signaling devices may be illuminated so that the said blades may be easily observed at night and 30 wherein the brackets employed to support the blades will each carry a mirror adjustable with respect to the driver's seat for reflecting traffic approaching in the rear of the driver.

35 Other and incidental objects will appear as the description proceeds. In the drawings wherein I have illustrated the preferred embodiment of the invention, and wherein similar reference characters designate corresponding parts throughout the several views:

Figure 1 is a fragmentary elevation showing my improved signal applied to the wind shield of a conventional type of motor vehicle, the semaphore blades of the signaling devices being illustrated in inactive position,

45 Fig. 2 is a view similar to Fig. 1 and showing the semaphore blade of one of the signaling devices in active position,

50 Fig. 3 is a fragmentary plan view more particularly illustrating the mounting of the semaphore blades of the signaling devices, the frame of the wind shield being shown in section,

55 Fig. 4 is a fragmentary perspective view

showing the female bearing plate for each of the semaphore blades,

Fig. 5 is a similar view showing the male bearing plate therefor,

Fig. 6 is a perspective view showing one 60 of the blades and its supporting plate detached,

Fig. 7 is a fragmentary sectional view 65 more particularly illustrating the mounting of the reflecting mirror employed upon each of the signaling devices, and

Fig. 8 is a fragmentary elevation showing 70 the stops employed for limiting each of the semaphore blades in its movement to active and inactive position.

In order that the construction, operation and mounting of my improved signal may 75 be accurately understood, I have, in the drawings, shown the signal in connection with the wind shield 10 of a conventional type of motor vehicle, a portion of the body of which is shown at 11. As is usual, the wind shield 10 is formed with a frame 12. In carrying out the invention, I employ 80 companion signaling devices indicated as a whole at 13 and 14 respectively. Since these devices are identical in construction, only one will be described in detail, the device 13 being shown. However, the reference numerals will be duplicated upon both of the 85 said devices. The signaling device 13 includes a supporting bracket comprising a preferably tubular arm 15 to the inner extremity of which are connected mating clamping members 15' adjustable to engage 90 with the frame 12 of the wind shield for supporting the arm to project laterally at one side thereof. Mounted upon the outer extremity of the arm 15 to seat against its rear side is a bearing plate or disk 16 secured to the said arm by spaced U-bolts 17.

This plate is, as preferably shown in Fig. 4 of the drawings, provided with substantially V-shaped grooves 18 arranged at right angles to each other. Overlying the plate 16 to coat therewith is a second bearing plate or disk 19. This plate is formed with diametric ribs 20 arranged at substantially right angles to each other and adapted to engage within the grooves 18 of the disk 16 100 so that the said plates normally seat flat against each other. Formed on the plate 19 at one side thereof is a radial wing 21 and riveted or otherwise secured to this wing is a suitable semaphore blade 22. The blade 105

22 is preferably given a coating of paint or enamel to furnish a red background for the representation of an arrow imprinted upon the side faces of the blade. Extending radially from the plate 19 at the side thereof opposite the wing 21 and disposed at an angle to the said wing is a lever arm 23 which, at its outer extremity is offset away from the bracket arm 15. Loosely fitted 10 through the outer extremity of the bracket arm to extend axially through the bearing plates 16 and 19 is a pivot rod 24 rotatably supporting the latter bearing plate. Formed on the rod to abut the arm 15 is a stop shoulder 25 and connecting the said rod with the arm is a nut 26 adjustable for rigidly clamping the rod in position. Mounted upon the outer extremity of the rod to confront the bearing plate 19 is a concavo convex reflector 27 open at its outer end. This reflector is preferably formed of suitable sheet metal and is provided at its inner extremity with a laterally projecting lug 28 loosely fitted upon the rod 24. Threaded upon the adjacent extremity of the rod is a nut 29 and interposed between this nut and the lug 28 of the reflector is a helical spring 30 surrounding the rod. Thus, it will be seen that this spring will hold the reflector in position tightly clamped against the bearing plate 19 and will also act to yieldably hold this bearing plate against the bearing plate 16 to coat therewith. The tension of the spring may be regulated by adjusting the nut 35. Threaded upon the outer extremity of the rod to seat against the nut 29 is a cap sleeve 31 formed at its outer end into a split socket 32 and adjustable within this socket is the ball 33 of a mirror bracket 34 carrying a mirror or reflector 35. Threaded through the socket to engage the ball 33 for holding the mirror at adjustment is, as particularly shown in Fig. 3 of the drawings, a set screw 35. It will thus be seen that the 40 mirror will be supported at the outer end of the rod 24 in such position that it may be easily adjusted with respect to the driver's seat of the vehicle for reflecting any traffic approaching from the rear of the vehicle. 45 Rotatably mounted in any approved manner upon the instrument board of the vehicle and extending freely through the vehicle cowl at the adjacent side thereof is a shaft 36 provided at its outer end with a crank 37 connected with the free end of the lever arm 23 by a link 38. Formed on the inner end of the said shaft is an operating crank 39 and in this connection it will be observed that the operating cranks of both of the signaling devices confront each other centrally of the instrument board of the vehicle so that both of the said cranks will be easily accessible from the driver's seat.

60 Formed on the periphery of the bearing plate 16 are spaced radial stop lugs 40 and

41 respectively, and formed on the periphery of the bearing plate 19 to project rearwardly therefrom over the edge of the plate 16 is a stop arm 42 adapted to selectively cooperate with the said lugs. 70

As will now be clear, the operating crank of the signaling device 13 may be readily grasped by the driver of the vehicle for rotating the bearing plate 19 of this signaling device upon the bearing plate 16 thereof and consequently swinging the semaphore blade 22 of the device from normal inactive position, as shown in Fig. 1, to horizontal active position, as shown in Fig. 2. When the semaphore blade is thus swung upwardly 80 the ribs 20 of the bearing plate 19 will be caused to ride out of the grooves 18 of the plate 16 and, when the semaphore blade reaches its active position, will then be caused by the spring 30 to again engage 85 within the said grooves for locking the semaphore blade in such position. When so disposed this signaling device will then indicate an intention of the driver to turn to the left, and it will be seen that upward movement of the semaphore blade will be limited by the engagement of the stop arm 42 of the bearing plate 19 with the stop 40 of the bearing plate 16 so that the said blade thus can not be swung beyond its active position. Reverse movement of the operating crank of the signaling device will, of course, again swing the semaphore blade downwardly to inactive position to be locked in such position by the engagement of the ribs 100 20 of the bearing plate 19, in the grooves 18 of the bearing plate 16. Downward movement of the semaphore blade will be limited by the engagement of the stop arm 42 with the stop 41 so that the said blade thus can not be swung beyond its inactive position. In like manner the operating crank of the signaling device 14 may be actuated for swinging the semaphore blade of this device upwardly to active position for indicating 105 an intention of the driver to turn to the right. The blade of the signaling device 14 will, of course, be locked in its active and inactive positions in the manner described with reference to the signaling device 13 and will be similarly limited in its movement in opposite directions. By swinging the semaphore blades of both of the signaling devices to active position, the driver may indicate an intention to stop. I accordingly provide 110 a signal which may be easily operated from the driver's seat for indicating an intention of the driver to turn either to the right or left or an intention to stop. The reflectors 27 of the signaling devices are adapted to support suitable lamp sockets therein and electric lamps positioned within these sockets may be connected with a storage battery or other suitable source of electrical energy upon the vehicle so that, at night, the 115 120 125 130

semaphore blades of the said devices will be illuminated by the said lamps. The inner sides and outer ends of the reflectors being open, light from the said lamps will be reflected along the semaphore blades so that the arrows thereon will be easily discernible.

Having thus described the invention, what is claimed as new is:

1. A traffic signal for motor vehicles including a supporting bracket having an arm, a bearing plate fixed against one side of the arm, a rod engaged with the arm and extending through said plate, the rod locking the plate against movement about the arm, a second bearing plate rotatably supported by the rod, a signal arm carried by the second plate, means for adjustably rotating the second plate to swing the signal arm, and coacting means between the plates for locking the second plate in adjusted position.
2. A traffic signal for motor vehicles including a supporting bracket, coacting bearing plates carried thereby, one of said plates being fixed and the other of the plates being rotatable upon the bracket, a signal arm carried by the second plate, means for adjustably rotating the second plate to swing the signal arm, and coacting means between the plates for locking the second plate in adjusted position.
3. A traffic signal for motor vehicles including a supporting bracket having an arm, a bearing plate rested against one side of the arm, U-bolts extending around the arm and connecting the plate therewith, a rod extending through the plate and arm, said rod being fixed to the arm and locking the plate against movement about the arm, a second bearing plate rotatable upon the rod, means for rotating the second plate, and a signal arm carried by the second plate.

In testimony whereof I affix my signature.

WILLIAM H. ROWLING. [L. S.]
